UNITED STATES PATENT OFFICE.

JAMES H. BOYD, OF WHITINSVILLE, MASSACHUSETTS, ASSIGNOR TO THE WHITIN MACHINE WORKS, OF WHITINSVILLE, MASSACHUSETTS, A CORPORATION OF MASSACHUSETTS.

TRAVERSE-MOTION FOR SPINNING AND WINDING MACHINES.

1,235,958.

Specification of Letters Patent.

Patented Aug. 7, 1917.

Application filed June 11, 1913. Serial No. 772,970.

To all whom it may concern:

Be it known that I, JAMES H. BOYD, a citizen of the United States, residing at Whitinsville, in the county of Worcester 5 and State of Massachusetts, have invented the following-described Improvements in Traverse-Motions for Spinning and Wind- ing Machines.

The invention is an improvement in the 10 builder motion for spinning and like machines and consists in the provision and structure of parts, such as exemplified by the device shown in the accompanying drawings, for forming a bunch on the base of the 15 bobbin for coöperation with the feeler of automatic replenishing looms, and involves simple and easily manipulated means for setting the machine so that it will operate either to produce a bunch wind on the bob- 20 bin or a smooth lay thereon, as may be pre- ferred. The invention also comprises the specific means above referred to in combina- 25 tion with certain other parts of the mecha- nism as will be hereinafter made apparent and as will be more particularly pointed out in the accompanying claims.

In the two sheets of drawings forming part hereof,

Figure 1 is a front elevation of so much 30 of an ordinary ring spinning frame, with parts in section, as will be necessary to illustrate the application of the invention there- to, it being understood that the invention is also applicable to analogous kinds of tex- 35 tile machinery.

Fig. 2 is an enlarged detail in longitudinal section of the pulley cradle and its bracket support.

Fig. 3 is a top plan thereof.

Fig. 4 is a side elevation of the same 40 viewed from the opposite side of the machine as shown in Fig. 1.

Fig. 5 is a detail on a still larger scale, of the pulley or rotary guide.

Fig. 6 is a detail of the filler thereof; and

Fig. 7 is a section of the pulley showing the means whereby the filler is secured thereto.

The numeral 1 represents the end stand- 50 ard of the spinning frame, 2 the usual bolster beam thereof bearing the spindles 3, and 4 represents the ring rail which is carried on rods 5, the latter being operated by the lifter

levers 6, as will be well understood by those familiar with this subject. The lifter levers 55 6 are connected through their sector arms 7, and a chain or like flexible connection, with the builder motion 8, which may be of any usual construction and ordinarily involves a builder lever pivoted on a stud 9 on the 60 end upright 1, such lever receiving an up and down motion from a builder cam 10, and its chain connections receiving an additional gain movement through the coöper- 65 ation of its ratchet wheel with a suitable pawl, as indicated in a general way in Fig. 1. The specific construction of the builder mechanism forms no part of the present invention and detailed description thereof will not therefore be necessary. It will of course 70 be understood that its function is to impart its oscillating movement through the lifter levers 6, and lifter rods 5, to the ring rail 4, so as to lay the yarn on the bobbin in any particular form of wind that may be de- 75 sired.

The means whereby the oscillating move- 80 ment of the builder mechanism transmits its movement to the sector arms 7 of the builder levers, comprises a chain 11 con- nected to the said oscillating lever and ex- 85 tends upwardly therefrom to a guide-pulley 12, to which the end of the chain is secured, as indicated at 11^a in Fig. 2. This guide pulley is a double tread wheel or 85 sheave journaled on an axle 13, which axle is carried in a cradle 14, and the cradle 14 is mounted so that it may rotate on its longi- 90 tudinal or horizontal axis in a gooseneck bracket 15, secured to the upright 1 directly 90 above the builder lever. As the builder lever oscillates on its horizontal stud 9, the angle of the stretch of chain 11 changes more or less from the vertical and the rotary 95 mounting of the cradle and its guide pulley serves to accommodate such change, so that the chain 11 will at all times be perpendicular to the axis or axle 13 of the rotary guide pulley, substantially in the manner shown and described in Patent No. 677,791, dated 100 July 2, 1901. The remaining portion of the flexible connection from the builder lever to the sector arm 7, comprises a stretch of chain 16 connected at one end to the said sector lever and at the other end with the 105 opposite tread of the rotary guide pulley, a

swivel 17 being included in the stretch to accommodate the swiveling action of the cradle and guide above referred to. The chain 11 in the present instance is secured 5 to the tread of the guide pulley which is toward the front of the machine as viewed in Fig. 1 and marked 12^a, and the chain 17 is secured to the tread 12^b in rear thereof, in such manner that the unwinding of the chain 10 from one tread produces the wind of the chain on the other tread, and vice versa. The two treads are desirably separated by a rim flange 12^c, and their chains are confined thereon by means of side flanges 12^d and 12^e, 15 respectively. The chains will thus be confined properly to the guide pulley when they are slack, as a doffing, notwithstanding the angular position which the guide pulley may hold in its bracket 15 at the time.

20 In normal operation the function of the guide pulley is first to change the direction of the up and down motion of the builder lever into horizontal motion of the chain 16 and the sector arms, and, second, to modify 25 such motion at the initial stage of the building action so as to affect the lay of the yarn upon the bobbin and produce a bunch thereon such as will be suitable for coöperation with the feeler of automatic looms, or for 30 any other purpose that may be desired. To this end the tread 12^b is mutilated or distorted, as, for example, by removing a segment thereof, as indicated in Fig. 5, leaving a flat surface 18 thereon, which is so located 35 as to be in contact with the chain 16 at the beginning of the winding action. This irregularity in the otherwise cylindrical surface of the pulley tread produces a relative dwell in the action of the chain 16 and the 40 parts which lift the ring rail, so that the desired bunch is formed near the base of the bobbin, but as the range of the traverse progresses toward the tip of the bobbin, gradually revolves to a position where it will 45 be out of contact with the chain and ineffective thereon, so that after the bunch has been formed the rest of the bobbin will be built with such wind as may be determined by the characteristics of the builder mech- 50 anism 8. When it is desired to build a smooth lay on the bobbin, as, for instance, when changing over to spin a warp yarn, the tread surface 12^b of the guide pulley is re- 55 stored to its cylindrical contour by inserting or replacing a removable part or segment, such as shown at 19 in Figs. 6 and 7. This attachment can be bolted to the body of the pulley by means of a bolt 20, as shown, and is provided with a rim flange 19^e which is 60 continuously circular with the rim flange 12^e, so as in effect to provide a plain circular tread for the chain 16. It will be observed, more particularly in Fig. 4, that the structure of the cradle 14, is such as to permit 65 access to the head of the bolt 20, without re-

moving the guide pulley therefrom, so that changing over from a bunch to a smooth wind, or vice versa, can be accomplished without inconvenience or complication.

By forming the guide pulley as a compound or double tread wheel, it may be as small as desired and yet bear a sufficient length of the chain 11 lapped thereon to accommodate the full traverse and gain movements necessary, but if size is not regarded 70 as of consequence, the pulley may be a single tread pulley and the chains 16 and 11 a single stretch of chain. In such case the single tread will be interrupted in the same manner as above described, to produce a 75 dwell of the traverse motion at the proper point and supplied with a removable and replaceable filler segment such as shown in Fig. 6, for changing over to a smooth lay. The function and mode of operation of the 80 distorted tread and its removable attachment will then of course be the same as in the case above specifically described and shown in the drawings. It will be understood by those skilled in this art that the mechanism 85 above described is not limited in respect of the details of its mechanical assemblage or construction, except as expressly specified in the claims hereto, and that various omissions, alterations and reversals may be re- 90 sorted to without departing from the invention.

I claim:

1. In a spinning frame, the combination 100 of a traversed rail, a builder motion comprising a flexible connection for operating the rail, a rotary guide for such connection having a slabbed-off portion, a segment complementary to said slabbed-off portion, and means for fixedly uniting the segment to 105 the guide and permitting removal thereof, whereby the guide may operate to produce either a bunch wind or a smooth lay on the bobbin.

2. In a spinning frame, the combination 110 of a traversed rail, a builder motion comprising a flexible connection for operating the rail, a rotary guide for such connection having a slabbed-off portion, a segment complementary to said slabbed-off portion, and means for fixedly uniting the segment to 115 the guide and permitting removal thereof, whereby the guide may operate to produce either a bunch wind or a smooth lay on the bobbin, said means being accessible at the 120 face of the guide.

3. In a spinning frame having a traversed rail and a builder mechanism, a connection comprising a guide pulley having double flanged treads, one tread being connected to 125 the builder mechanism and the other to the traversed rail, and one tread having a cut-away portion, in combination with a segment formed to complete the contour of said cut-away tread, and means for passing 130

through said segment from the face thereof into the other tread portion to secure the segment in place and permit removal thereof.

5 4. A guide pulley for builder motions provided with double treads and chain-confining flanges, a section of said pulley at one side comprising a portion of one of the treads and of its outside flange being remov-

able and having means for securing the same 10 in place.

In testimony whereof, I have signed this specification in the presence of two witnesses.

JAMES H. BOYD.
